UNITED STATES PATENT OFFICE.

JACOB G. WISSINGER, OF RUTHERFORD, NEW JERSEY.

PROTECTOR FOR LAMPS.

1,243,236.

Specification of Letters Patent. Patented Oct. 16, 1917.

Application filed November 3, 1916. Serial No. 129,342.

To all whom it may concern:

Be it known that I, JACOB G. WISSINGER, a citizen of the United States, and resident of Rutherford, in the county of Bergen and State of New Jersey, have invented a new and useful Improvement in Protectors for Lamps, of which the following is a specification.

This invention relates to an improvement in protectors for lamps, with the object in view of providing a device which may be mounted upon the reflector of the conventional type of lamps used upon automobiles, whereby the upward and side glare of the lamp will be dimmed.

Another object is to provide a device which may be adjusted to fit reflectors of various sizes.

Another object is to provide a device which is marked with a series of concentric indicating lines, which lines act as a guide for the user to cut the blank to properly fit the particular reflector to which it is to be used.

Another object is to provide a device which is simple, effective and cheap to manufacture.

Another object consists in providing certain improvements in the form, construction and arrangement of the several elements whereby the above named and other advantages may be effectively carried out.

A practical embodiment of my invention is represented in the accompanying drawings, in which,

Fig. 1 represents a front elevation partly in section, of a lamp having my improved device applied thereto.

Fig. 2 represents a vertical central section taken in the plane of the line II, II, of Fig. 1, and

Fig. 3 represents a plan view of my device laid out flat and forming a blank.

The device in a blank is of semicircular form, having a body portion 1, and wings 2, 3, formed by a radial slit 4, extending from its periphery toward the center and terminating at its inner end in a curved slit 5. The body 1 has a hole 6 which is reinforced by washers 7 and by which the device is supported in its position on the lamp. The wings 2, 3, are provided with upwardly extended tips 8, 9, the purpose of which will be hereinafter explained. The wing 2 is provided with a tongue 10 which is arranged to coact with one of the slots 11 in the wing 3, to retain the wings in a locked position

when in use, the particular slot registering with the tongue according to the diameter or size of the lamp. The wings are also provided with indicating lines 12 drawn parallel with the outer periphery, by which lines the user may be guided so as to cut the wings to fit the particular lamp to which it is to be used.

After the wings have been cut to the desired size, the device is applied to the reflector 13 of the lamp, by removing the incandescent bulb 14, which is again replaced with the washers 7 and body 1 interposed between the shoulders 15 of the bulb and the socket 16 of the lamp. With the bulb screwed down to its proper position, the device is firmly held against rotation. In this position, as shown in Figs. 1 and 2, the wings are overlapped so that they will conform to the shape of the reflector 13, while the tongue 10 is fitted in the slot 11 nearest thereto. With the wings secured in position, the lower half of the reflector will be covered, thereby diffusing the rays of the incandescent bulb. To eliminate the side glare of the reflector, the tips 8 and 9 of the wings 2, 3 are extended upwardly above a horizontal line and thus cover a portion of the side of the reflector. The remaining portion of the reflector left uncovered directs the rays of the bulb downwardly and below the vision of a person passing in front of the lamp, at the same time affording sufficient light to meet all requirements.

The device may be made of flexible sheet material such as paper or other suitable material, which is opaque and of sufficient flexibility that it will conform to the different shapes of the reflectors now in common use.

What I claim is:

1. A lamp glare protector of flexible sheet material comprising a body portion 100 having wings integral therewith, said wings being adapted to conform to the shape of the lamp reflector when in use.

2. A lamp glare protector of flexible sheet material comprising a body portion 105 having adjustable wings integral therewith, said wings being adapted to overlap to conform to the shape of the lamp reflector, when in use.

3. A lamp glare protector of flexible sheet material comprising a body portion 110 having adjustable wings integral therewith,

- said wings being adapted to overlap to conform to the shape of the lamp reflector, and means for retaining the wings in locked engagement when in use.
5. A lamp glare protector of flexible sheet material comprising a body portion having adjustable wings integral therewith, said wings being adapted to overlap to conform to the shape of the lamp reflector, 35
- 10 said wings having a tongue and slot engagement for retaining them in locked position when in use.
5. A lamp glare protector of flexible sheet material comprising a body portion 15 having adjustable wings integral therewith, said wings being adapted to overlap to conform to the shape of the lamp reflector when in use, said wings having a tongue and slot engagement for retaining them in 20 locked position when in use and provided with upwardly extended tips.
6. A lamp glare protector of flexible sheet material comprising a body portion having a hole therein for the reception of 25
- 25 an incandescent bulb, adjustable wings integral therewith, said wings being adapted to overlap to conform to the shape of the lamp reflector, said wings having a tongue and slot engagement for retaining them in 30 locked position when in use.
7. A lamp glare protector of flexible sheet material comprising a body portion
- having a reinforced hole therein for the reception of an incandescent bulb, adjustable wings integral therewith, said wings 35 being adapted to overlap to conform to the shape of the lamp reflector, said wings having a tongue and slot engagement for retaining them in locked position when in use and provided with upwardly extended 40 tips.
8. A lamp glare protector of flexible sheet material comprising a semicircular blank having a series of concentric indicating lines for trimming to fit lamps of different diameters. 45
9. A lamp glare protector of flexible sheet material comprising a semicircular blank divided by communicating radial and transverse slits. 50
10. A lamp glare protector of flexible sheet material comprising a semicircular blank divided by communicating radial and transverse slits and having a series of concentric indicating lines for trimming to fit 55 lamps of different diameters.
11. A lamp glare portector of flexible sheet material comprising a semicircular blank having a radial slit terminating at its inner end in a curved slit. 60

In testimony, that I claim the foregoing as my invention, I have signed my name this 1st day of November, 1916.

JACOB G. WISSINGER.
